UNITED STATES PATENT OFFICE.

HOMER LAUGHLIN, JR., AND DANIEL SCHUYLER, OF LOS ANGELES, CALIFORNIA, ASSIGNORS TO THE PERFECT SLIDING DOOR COMPANY, OF LOS ANGELES, CALIFORNIA, A CORPORATION OF CALIFORNIA.

PUSH-BUTTON FOR LOCKS, &c.

SPECIFICATION forming part of Letters Patent No. 694,341, dated February 25, 1902.

Application filed July 10, 1901. Serial No. 67,804. (No model.)

To all whom it may concern:

Be it known that we, HOMER LAUGHLIN, Jr., and DANIEL SCHUYLER, citizens of the United States, residing at Los Angeles, in the county of Los Angeles and State of California, have invented a new and useful Push-Button for Locks and other Purposes, of which the following is a specification.

The object of this invention is to provide a cheap, durable, and attractive push-button to be operated through a perforation in any member where the push-button is to be used.

Our push-button may be used for the night-latch mechanism of door-locks, for mechanism of camera-shutters, push-buttons for electrical devices, push-buttons for door-operating devices, and for any and all uses in which a push-button is required.

An object of our invention is to provide a push-button which will of itself take up any play between the push-button and the part to be operated thereby.

Another object is to provide a maximum pushing-surface and guiding-body and a maximum strength with a minimum amount of material.

Our invention may be carried out in various different forms and can be made of various kinds of materials.

The accompanying drawings illustrate our invention in some of the forms in which it may be carried out.

Figure I shows our newly-invented push-button as applied in a night-latch lock, a portion of which latch is shown. Fig. II is a mid-sectional view of the push-button detached. Fig. III is a mid-sectional view of a modified form of the push-button.

Our newly-invented push-button consists in a tubular body 1, furnished with extensions 2, which are integral with the walls of the tube. These extensions are preferably resilient and are brought into any form which is applicable for the use to which the push-

button is to be applied. Preferably the push-button is formed in a cup, as shown at 11 in Fig. I, and the extensions 2 are integral with the edge of the cup. In practical manufacture said cup 11 will be made of drawn sheet metal.

In Fig. I, 3 indicates a member to which the push-button is connected by the resilient members 2, said resilient members being arranged to tightly clasp said member 3 between them. 4 indicates a pivotal rivet pivoting the push-button to the member 3, to be operated.

In Fig. III the tubular member is open at its ends, and 5 indicates a cap for the end of the tube to close the same.

It is to be understood that the push-button may be made of any size and may be operated by the finger, hand, or foot, or by any device adapted for the purpose.

What we claim, and desire to secure by Letters Patent of the United States, is—

1. A push-button consisting in a cup furnished with extensions which are integral with the edge of the cup.

2. A push-button consisting in a cup furnished with perforated extensions which are integral with the edge of the cup.

3. A push-button consisting in a tubular body furnished with extensions which are integral with the walls of the tube.

4. A push-button consisting in a tubular body furnished with resilient extensions which are integral with said body.

In testimony whereof we have signed our names to this specification, in the presence of two subscribing witnesses, at Los Angeles, California, this 8th day of June, 1901.

HOMER LAUGHLIN, JR.
DANIEL SCHUYLER.
